UNITED STATES PATENT OFFICE.

CLARENCE GASTON WALKER, OF BRAMWELL, WEST VIRGINIA.

ATTACHMENT FOR COAL-CONVEYERS.

1,375,988.

Specification of Letters Patent. Patented Apr. 26, 1921.

Application filed November 3, 1919. Serial No. 335,410.

To all whom it may concern:

Be it known that I, CLARENCE GASTON WALKER, a citizen of the United States, and a resident of Bramwell, in the county of 5 Mercer and State of West Virginia, have invented certain new and useful Improvements in Attachments for Coal-Conveyers, of which the following is a specification.

My invention relates generally to coal mining machinery, and particularly to an 10 attachment for stationary or movable conveyers, the purpose of my invention being the provision of a simple and inexpensive device which can be readily attached to a 15 conveyer for automatically controlling the passage of coal therefrom to prevent breakage of the coal and to uniformly distribute the coal to a second conveyer.

In coal conveying machinery, there is al- 20 ways a gap of six or more inches between any two adjacent conveyers and the coal in dropping from the upper conveyer to the lower conveyer is invariably broken into small particles and is not uniformly dis- 25 tributed so that it is deposited onto the lower conveyer exactly as it is introduced into the upper conveyer, which is generally by the car-load.

In carrying out my invention, I over- 30 come these objections by providing a plurality of flexible members, such as chains or the like, which are connected preferably at regular spaced intervals to the delivery end of the upper conveyer so that they depend 35 from such end and rest on the lower conveyer in a manner to form an inclined plane which spans the gap between the conveyers and over which the coal is caused to pass when leaving the upper conveyer. Because 40 of the flexibility of these members a flexible inclined plane is produced which gives to a limited degree, under the weight of the coal, as it impinges thereupon, so that a cushioning effect is obtained which retards 45 the movement of the coal and thus prevents breakage thereof in passing from one conveyer to the other. This cushioning effect is increased to a marked degree by reason 50 of the fact that portions of the members which lie on the lower conveyer are practically fixed against any great longitudinal movement by the coal which rests on these portions so that the members are prevented from completely collapsing under the weight

and the action of the coal dropping from the 55 upper conveyer, whereby the inclined position of the members is maintained. This cushioning effect is further increased as result of the slack and smaller lumps of coal which accumulate between the members, 60 thus tending to make the members more rigid and to maintain their spaced relation enabling them to properly cushion large lumps of coal even when they strike the members with great force. Because of the 65 spaced relation of the flexible members, a uniform distribution of the coal to the lower conveyer is naturally effected, so that when a large quantity of coal is introduced into the upper conveyer, it will be gradually and 70 uniformly fed to the lower conveyer, whereby the subsequent handling of the coal is materially facilitated.

The forms, size, length and distance between adjacent members may be varied to 75 a wide degree depending upon the kind and grade of coal to be handled. For instance, the flexible members may be arranged upon the delivery end of the upper conveyer in the form of loops, or only one end of the mem- 80 bers may be secured to the conveyer while their free ends repose upon the lower conveyer. In the latter form, every other member in the combination may be shorter in length than the other members, the short 85 and long members coacting to effect a cushioning of the smaller lumps of coal and to reduce the amount of retardation so as to effect a quicker feeding of the coal from one conveyer to the other. Should the 90 amount of retardation be excessive, it can be regulated by shortening the members, spacing them farther apart or using different size members.

Various forms of flexible members and 95 manners of applying the same to various forms of conveyers may be employed other than those above mentioned but the present preferred embodiment of my invention is illustrated in the accompanying drawings, 100 in which:

Figure 1 is a view, showing in perspective one form of device embodying my invention applied to one form of conveyer and resting upon a second form of conveyer; 105

Fig. 2 is a longitudinal sectional view of Fig. 1;

Fig. 3 is a top plan view; and

Fig. 4 is a fragmentary detail view, showing the manner in which the flexible members are connected to the upper conveyer.

Similar reference characters refer to similar parts in each of the several views.

Referring specifically to the drawings, C designates the upper conveyer which in the present instance is in the form of a chute including a bottom wall 15 and side wall 16. The chute C is adapted to convey coal to the lower conveyer C' which in the present instance is a picking table that is continuously movable in the direction of the arrow in Fig. 2, and is formed of hinged sections 17 which are connected by joints 18 that extend transversely of the table and rise above the bottom wall of the same so as to provide ridges.

The device embodying the subject-matter of my invention is herein shown as comprising a plurality of chains H each of which is connected at one of its ends to the delivery end of the chute C. As shown in Fig. 3, the lower marginal edge of the bottom wall 15 of the chute is formed at regular spaced intervals with openings which receive bolts 19 that project to the lower side of the wall and carry the uppermost links of the chains H. With the chains H attached to the chute in this manner, their lower or free ends lie upon the bottom wall of the picking table C' in such manner that the portions adjacent their upper ends are inclined, as at 20, in Fig. 2 to provide the flexible inclined plane hereinbefore mentioned. As the picking table C' moves in the direction of the arrow in Fig. 2, the joints 18 successively engage the chains H and thereby impart a wave-like motion to the chains, which motion is in the direction of the free ends of the chains with the starting point adjacent the inclined portions 20. As the result of this wave-like motion, the coal coming from the chute C is fed off of the chains in a uniform manner such coal scattering out on the picking table uniformly so that the subsequent cleaning of the coal by hand is materially simplified. It will be noted that as the joints 18 engage all of the chains H simultaneously, a wave extending all the way across the several chains is effected so that they move as a unit, each chain depositing approximately the same amount of coal each time a joint 18 passes under them. As illustrated to advantage in Fig. 1, the smaller particles of coal accumulate between adjacent chains H, thus preventing the chains from moving laterally from their normal positions and cushioning the succeeding coal which is discharged from the chute. As further illustrated, the large particles of coal repose on the free ends of the chains which has a tendency to stretch the chains and thus make them rigid, thereby

providing an additional means for preventing relative lateral movement of the chains and maintaining the inclined portions 20.

Although I have herein shown and described only one form of device embodying my invention and one manner of using the same, it is to be understood that various changes and modifications may be made herein without departing from the spirit of the invention or the spirit and scope of the appended claims.

Having thus described my invention, I claim:

1. In combination, two conveyers arranged one above the other, and a plurality of chains secured to the upper conveyer and having portions thereof lying upon the lower conveyer in a manner to span the space between the conveyers.

2. In combination, two conveyers arranged one above the other, and a plurality of flexible members secured to the upper conveyer at regular spaced intervals and depending therefrom to provide a flexible inclined plane between the two conveyers.

3. In combination, a chute, a picking table disposed below said chute and comprising hinged sections having joints disposed above the bottom wall of the table and extending transversely thereof, and a plurality of flexible members secured to the delivery end of the chute and having their free ends lying on the picking table and adapted to be engaged by said joints for imparting a wave-like motion to the members when the picking table is moved.

4. A device of the character described comprising a plurality of flexible members adapted to be secured to the delivery end of a conveyer in such manner that portions of the members lie upon the picking table to provide inclined portions between the chute and table.

5. In combination, a conveyer, and a plurality of flexible members secured to the delivery end of said conveyer and depending therefrom.

6. In combination, a conveyer, and a plurality of chains secured at one of their ends to the delivery end of said conveyer, with their free ends depending from said conveyer.

7. In combination, a conveyer, and a plurality of chains secured at one of their ends to the delivery end of said conveyer, said chains being secured at regularly spaced intervals upon said conveyer.

8. In combination, two conveyers arranged one above the other, and a flexible inclined plane made up of flexible independently movable sections secured to and depending from the delivery end of the upper conveyer and having a portion thereof resting upon the lower conveyer.

9. In combination, two conveyers ar-

ranged one above the other and adapted to convey coal from the upper conveyer to the lower conveyer, and flexible means carried by the upper conveyer and contacting 5 with the lower conveyer for controlling the passage of coal therefrom so as to uniformly distribute the coal onto the lower conveyer and to prevent breakage thereof during its passage.

10 10. In combination, a delivering conveyer,

and a traveling receiving conveyer, and means controlled by the receiving conveyer for controlling the passage of the material from the delivering conveyer to the receiving conveyer so as to uniformly distribute 15 the material onto the receiving conveyer and to prevent breakage thereof during its passage.

CLARENCE GASTON WALKER.
